UNITED STATES PATENT OFFICE.

GEORGE MERKEL, OF RICHLFIELD, WISCONSIN, ASSIGNOR OF TWO-THIRDS TO GEORGE BERNERT AND JACOB BERNERT, OF RICHLFIELD, WISCONSIN.

GRAIN-BLOWER.

SPECIFICATION forming part of Letters Patent No. 754,476, dated March 15, 1904.

Application filed December 3, 1903. Serial No. 183,569. (No model.)

To all whom it may concern:

Be it known that I, GEORGE MERKEL, a citizen of the United States, and a resident of Richfield, in the county of Washington and State 5 of Wisconsin, have invented certain new and useful Improvements in Grain-Blowers; and I do hereby declare that the following is a full, clear, and exact description thereof.

My invention relates to pneumatic devices 10 for transferring grain from one place to another; and it consists in certain peculiarities of construction and combination of parts, as will be fully set forth hereinafter in connection with the accompanying drawings and subsequently claimed.

In the said drawings, Figure 1 is a view, partly in elevation and partly in section, on the plane indicated by the line 1 1 in Fig. 3, of a structure embodying my present invention. Figs. 2 and 3 are transverse sectional views taken, respectively, on the planes indicated by the lines 2 2 and 3 3 in Fig. 1.

Referring by numerals to the said drawings, 1 designates a standard or frame serving as a support for a circular casing 2, formed with a central opening 3 in its base, through the center of which opening there extends the vertical shaft 4 of a fan, the blades 5 5 5 of which are secured to the lower side of a solid 30 circular disk 6, which latter has an under side hub 7 for the reception of the top of the shaft 4, fastened thereto by pin 8. The casing 2 has an outlet communicating with a pipe or passage-way 9, leading to the place to which the grain is to be transferred, and an inlet, to be presently described.

On the upper face of the fan-disk 6 are secured a series of curved strips 10 10 10, which, like the fan-blades 5 below, are arranged radially about the center, there being a central space corresponding to the diameter of the adjustable end 11 of the feed-pipe 12, and each strip 10 extends from the annular line of this space to an annular line a short distance 45 within the periphery of the disk 6.

The feed-pipe 12 is supported above the fan by the upper part of the casing 2, which has a flanged opening of just sufficient size to ad-

mit said pipe, which is secured to the casing-flange, as by bolts or rivets 13 13. The upper 50 end of said pipe 12 terminates in a hopper 14, and the lower end is surrounded by the adjustable pipe end 11, just referred to, which may be lowered to any point desired between the lower end of the feed-pipe proper, 12, and 55 the upper face of the solid revolving fan-disk 6 and there made fast. In the present illustration this is accomplished by the following means: 15 is a band vertically movable on the pipe 12 and provided with a set-screw 16 to 60 stop same by impingement on the pipe. This band 15 carries links 17 17, whose lower ends engage with pins 18 18 on the pipe end 11. The shaft 4 has a pulley 19 fast thereon, revolved by a belt 20 from any suitable source 65 of power.

The operation of my device will be readily understood from the foregoing description of its construction, taken in connection with the accompanying drawings. Grain is fed into 70 the hopper 14 and falls through the feed-pipe 12 11 onto the center of the solid plate or disk 6, this feed being regulated by the adjustable pipe end 11, which can be lowered so as to partly or entirely cut off said supply 75 or raised up to increase the flow. The pipe or passage-way 9 leads to the point of discharge of the grain, and the outlet from the casing 2 to said pipe or passage-way extends both above and below the line of the described fan-disk 6. 80 As the shaft 4 is rapidly revolved the grain on the disk 6 is carried by centrifugal action to the edge of the said disk, the curved strips 10 10 serving to distribute the grain evenly and prevent an accumulation at any one point, 85 and the current of air from the blades 5 5 on the under side of the disk 6 will serve to draw the grain on the disk through the outlet and into the pipe or passage-way 9 and below it to the desired point to which it is to be transferred, thus making a very simple, practical, 90 and efficient grain-blower.

I have shown the standard or frame 1 bolted to the casing 2; but it will be understood that said casing may be revoluble on the standard, 95 so that the outlet and communicating pipe or

passage-way 9 may point in any direction. It will also be understood that my device is intended to be used in connection with a threshing-machine, with the hopper placed directly under the weigher, so that the grain therefrom will be carried directly to a bin or other point desired.

Having thus described my invention, what I claim as new, and desire to secure by Letters Patent, is—

10. 1. In a grain-blower, the combination with a suitable standard or frame, and a circular casing supported thereon, said casing being provided with central openings at the top and bottom, and a side outlet in communication with a pipe or passage-way, of a revoluble vertical shaft, extending up within said casing; a solid circular disk secured to the upper end of said shaft; a series of radially-disposed fan-blades secured to the under side of said disk; a series of radially-disposed strips secured to the upper side of said disk; and a feed-pipe extending down through the upper opening of the said casing toward the said circular disk.
15. 2. In a grain-blower, the combination with a suitable standard or frame, and a circular casing supported thereon, and provided with an

upper and a lower central opening, and an outlet-opening in its side wall of substantially the height of said casing, of a pipe or passage-way 30 in communication with said outlet-opening; a revoluble vertical shaft, extending up through said lower opening and terminating on a line intermediate of the top and bottom of said outlet-opening; a solid circular disk secured to the upper end of said shaft, and of a diameter to just revolve within said casing; fan-blades on the lower side of said disk, and curved guiding and distributing strips on the upper side of the disk; a feed-pipe extending down through the upper opening of the casing; a vertically-movable pipe end fitting lower end of said feed-pipe; and means for varying the projection of the pipe end beyond the lower end of the feed-pipe, and for holding the said pipe end 45 in any position to which it may be adjusted.

In testimony that I claim the foregoing I have hereunto set my hand, at Richfield, in the county of Washington and State of Wisconsin, in the presence of two witnesses.

GEORGE MERKEL.
